UNITED STATES PATENT OFFICE.

ROBERT E. BROWN, OF OLEAN, NEW YORK.

RAZOR HONE AND STROP.

1,332,101.

Specification of Letters Patent. Patented Feb. 24, 1920.

Application filed March 14, 1918. Serial No. 222,401.

To all whom it may concern:

Be it known that I, ROBERT E. BROWN, a citizen of the United States, residing at Olean, in the county of Cattaraugus and 5 State of New York, have invented certain new and useful Improvements in Razor Hones and Strops, of which the following is a specification.

This invention relates to razor hones and 10 strops and has as its primary object to provide a simple and compact device embodying both a hone and a stropping surface.

The invention further has as its object to provide a device of the class described above so constructed that the hone side of the device may be placed face down upon a table or the like without likelihood of injury to the hone and without depositing upon the surface upon which the device is 15 laid, any oil, lather, or water which has been applied to the honing surface.

Another object of the invention is to provide a stropping surface which will possess the desired degree of yieldability so 20 that its effect upon the razor edge will be substantially the same as that of an ordinary suspended strop, one end of which is held in the hand while stropping in the ordinary manner.

At the present time the tendency is to 25 manufacture devices of this nature having a relatively short honing surface and, therefore, the invention has as a further object to provide a combined honing and stropping 30 device embodying a relatively short honing surface and yet having a relatively long stropping surface.

In the accompanying drawings:

Figure 1 is a perspective view of the device embodying the present invention;

Fig. 2 is a vertical transverse sectional view on the line 2—2 of Fig. 1;

Fig. 3 is a vertical longitudinal sectional view through a modified form of the structure shown in Fig. 1;

Fig. 4 is a perspective view illustrating a further modification of the invention;

Fig. 5 is a side elevation of a still further modified form of the device.

In all forms of the device illustrated, the same consists generally speaking of a body which may be of wood, or any other suitable material, and which is provided upon one face with a hone, the other face of the body 55 having applied to it a sheet of felt or other yieldable material to which in turn is ap-

plied a sheet or strip of leather to constitute the stropping surface. In that form of the invention shown in Fig. 1, the body, which, as above stated, may be of wood or 60 any other material, is indicated in general by the numeral 1 and one face of the body, which face is indicated in general by the numeral 2, is provided at each end with a transversely extending bulged portion 3, the 65 said portions constituting rests for supporting the face 2 of the body in spaced relation to a surface upon which the said rests 3 are disposed. In the intermediate portion of its length, the face 2 of the body 1 70 is formed with a depression or recess 4 which extends transversely of the said face 2 and in the present instance the entire width thereof although the recess may terminate short of the lateral edges of the 75 body 1 if found desirable. Disposed and secured in any suitable manner as by adhesive, within the recess 4, is a hone block indicated by the numeral 5, the face of the 80 hone lying beyond the plane of the face 2 of the body 1, but being spaced inwardly of the plane occupied by the engaging portions of the rests 3. Viewing the structure in another light, the body 1 may be considered as formed in its face 2 with a de- 85 pression which results in the rest portions 3. The opposite face of the body 1, indicated by the numeral 6, constitutes a plane surface to which is secured in any suitable manner, as for example by adhesive, one 90 face of a sheet 7 of felt or other yieldable material, the said sheet preferably covering the entire area of the face 6 and being of any desired thickness and degree of compactness. Suitably secured to the other or 95 outer face of the sheet 7 is a sheet or strip 8 of leather or any composition of materials providing a stropping surface. From the foregoing description of this form of the invention it will be understood that the hone 100 5 may be made relatively short and located either midway between the ends of the body 1 or nearer one end than the other. It will also be understood that as the face of the hone is spaced inwardly from the plane oc- 105 cupied or touched by the engaging surfaces of the rests 3, the device as a whole may be disposed upon the surface of a table or the like in the manner shown in Fig. 1 of the drawings without likelihood of the surface 110 of the hone coming in contact with the said surface which would be likely to result in

scratching of the hone or injury thereto or to the said surface, or in depositing upon the surface oil, water, or lather previously applied to the face of the hone. It will 5 further be apparent that the sheet 7 being yieldable, provides a yieldable support or backing for the stropping sheet 8 so that as the razor is moved backwardly and forwardly over this surface and pressure is 10 applied, the surface will yield in substantially the same manner as the surface of a suspended strop one end of which is held in the hand during the operation of stropping the razor.

15 In that form of the invention shown in Fig. 3 of the drawings, the stropping sheet is indicated by the numeral 9, the yieldable backing therefor by the numeral 10, the body by the numeral 11, and the hone block 20 by the numeral 12. In this form of the invention as in the previously described form, the stropping sheet 9, and the backing sheet 10 extend the full width and length of the face of the body 11 to which they are applied and secured. However, in this form instead of the hone 12 being relatively short, the same extends the entire length of the other face of the body 11, which face is indicated by the numeral 13, and the said face is 25 provided at its end with rests 14 corresponding to the rests 3, the ends of the hone block 12 abutting against the inner or opposed sides of the said rests 14. In this form of the invention, however, as in the previously 30 described form, the working surface of the hone block 12 is spaced inwardly of the plane of the engaging portions of the rests 14 for the purpose previously explained.

35 In that form of the invention shown in Fig. 4 of the drawings, parts corresponding to the parts illustrated in Fig. 3 are indicated by corresponding reference numerals. However, in this form the face 13 of the body 11 may be provided with a relatively 40 shallow recess to receive the hone block 12,

the recess being in fact of a depth less than the thickness of the said block so that the equivalent of the rests 3 and 14, previously described, is not present in the form shown in Fig. 4. However, similar rests may be 50 present as the principal difference between this form of the invention and the previously described forms lies in the provision at one end of the body 11 of a suitable handle 15 whereby the device as a whole 55 may be conveniently held stationary and otherwise manipulated.

In that form of the invention shown in Fig. 5 of the drawings, the stropping sheet is indicated by the numeral 16, the yieldable backing by the numeral 17, the body by the numeral 18, and the hone block by the numeral 19, and in this form of the device all of the elements enumerated have their corresponding edges in registration so that the device as a whole is rectangular, the stropping surface extending over the entire area of one face of the body 18 and the hone block 19 extending over the entire area of the other face of the said body.

70 Having thus described the invention, what is claimed as new is:

In an article of the class described, a stock having a stropping sheet secured upon one of its faces, and a hone secured to the 75 other face of the stock, the stock having its last mentioned face depressed to provide rests at the ends thereof and the said hone having its working face located in a plane spaced inwardly of the plane of the engaging portions of the rests, the space between the rests and opposite the face of the hone being unobstructed, whereby when the stropping surface is in use the article may be disposed upon its rests with the said working 80 face of the hone spaced above the surface engaged by the said rests.

85 In testimony whereof I affix my signature.

ROBERT E. BROWN. [L. S.]
